UNITED STATES PATENT OFFICE.

AINSWORTH BUCK, OF SUMMIT, NEW JERSEY.

WINDOW-CLEANER'S SAFETY ANCHOR.

Application filed June 27, 1922. Serial No. 571,211.

The invention relates to window cleaners' safety devices, and more particularly in certain of its features to the mounting on, and fastening thereof to, the window frame.

5 Objects and advantages of the invention will be set forth in part hereinafter and in part will be obvious herefrom, or may be learned by practice with the invention, the same being realized and attained by means 10 of the instrumentalities and combinations pointed out in the appended claims.

The invention consists in the novel parts, constructions, arrangements, combinations and improvements herein shown and de- 15 scribed.

The accompanying drawings, referred to herein and constituting a part hereof, illustrate one embodiment of the invention, and together with the description, serve to ex- 20 plain the principles of the invention.

Of the drawings:—

Fig. 1 is a horizontal section through a window frame and adjoining building structure and showing the window cleaner's anchor in place with reference thereto;

Fig. 2 is an isometric perspective of the anchor;

Figs. 3 and 4 are views corresponding to the lower right hand end of Fig. 1, and showing respectively, a somewhat different form of fastening for the anchor on the window frame.

In the accompanying drawings, illustrating by way of example one embodiment of the invention, the safety device of the invention is shown applied to one standard or commercial form of metal window frame, although it will be understood that the invention is equally applicable to other forms 10 of window frames.

In Fig. 1, a window sash is shown at 1 with the glass 2 mounted therein, the sash running in the guideway 3 in the frame and having a weather-tight bearing at 4. The exterior, vertically-disposed hollow side member of the window frame, commonly called the staff molding, is shown at 5. As stated, however, the details of this particular form of metal window frame are 45 merely shown in an exemplary way.

Referring now to the present preferred embodiment of the invention, it is provided with a head 10 and a neck 11, the attachment upon the window cleaner's belt slipping over the head 10 in the usual manner. The neck 11 is mounted on and projects

from the body of the safety device. The body of the safety device is shaped to embrace a part of the window frame, and preferably is yoked to straddle the staff 60 molding 5, and to engage therewith on three sides thereof.

For this purpose the body has a front or intermediate portion 12, the interior face of which bears upon the front face of the staff 65 molding 5, and has side members 13 and 14, extending inwardly from either side of the body 12, and fitting closely about the opposite side walls 15 and 16 of the staff molding 5. Thus the safety device fits snugly 70 upon three walls or faces of the staff molding, the backwardly-extending side members of the safety device extending preferably well back along the side walls of the staff molding. 75

There is preferably provided also at the inner end of the inner side wall 14 of the safety device a vertically disposed flange 17 extending away from the wall 14 of the safety device, and adapted to project within 80 and behind the masonry or other building element 18.

Means are provided for attaching the safety device to the window frame, and as 85 preferably embodied the fastening means pass through both the side members 13 and 14 and through both the side walls of the staff molding 5. In Fig. 1, a rivet 20 is shown arranged and disposed as just described, having its heads 21 and 22 on the 90 outer sides, respectively, of the side members 13 and 14 of the safety device.

In Fig. 3, a bolt 23 is shown screw-threaded into both the side wall 16 of the staff molding and the member 14 of the safety 95 device. The bolt threaded thus into these two members will naturally lock in position. In Fig. 4 a bolt 24 is shown, passing through both the side members of the safety device and both the side walls of the staff molding, 100 and screw-threaded into the side member 14 of the safety device, and having a nut 25 screwed thereon to hold it in position. The nut 25 may be set in the mortar or cement of the masonry which will prevent 105 its becoming unscrewed and will lock it in position.

The safety device may be attached to the window frame before it is put in position, or after it is put in position, but independently 110 of the setting of the masonry, and yet the masonry cooperates to take a certain part

of the strain if necessary. The safety device is unusually strong in view of its snug three-sided fit on the window frame, the side members of the device taking most of the strains which may be applied thereto, the rivet, nut or like fastening merely keeping the device in fixed vertical position.

It will be understood that variations may be made from the exact structure shown and described, within the scope of the accompanying claims, without departing from the principles of the invention and without sacrificing its chief advantages.

What I claim is:—

15. 1. A window cleaner's safety anchor comprising a U-shaped body adapted to embrace and bear on three faces of a window frame member, a head projecting from said body, means for fastening said anchor to a window frame, said U-shaped body having an inner angularly projecting flange adapted to extend between a part of the window frame and the masonry of a building.
20. 2. A window cleaner's anchor, comprising a U-shaped yoke adapted to straddle a portion of the window frame and engage it on three sides, a securing pin passing through both sides of the yoke and through the window frame, and a head projecting diagonally from one corner of the yoke.
25. 3. A window cleaner's anchor, comprising a U-shaped yoke adapted to straddle a portion of the window frame, one of the sides of the yoke being turned outwardly to form a holding flange, means for securing the yoke to the window frame so that it engages therewith on three sides, and a head pro-

jecting diagonally from one corner of the yoke.

4. A window cleaner's anchor, comprising a substantially U-shaped yoke adapted to straddle a portion of the window frame, one of the sides of the yoke being turned outwardly to form a holding flange, a securing pin passing through both sides of the yoke and through the window frame, and a head projecting diagonally from one corner of the yoke.

5. A window cleaner's anchor, comprising a vertically-disposed metal plate having a front part and two side parts projecting backwardly therefrom and adapted to fit closely about the front and sides of a window frame member, a head projecting from the front of the plate member, and a single fastening bolt passing through both sides of the window frame member and through both side parts of the plate member.

6. A window cleaner's anchor, comprising a vertically-disposed metal plate having a front part and two side parts projecting backwardly therefrom and adapted to fit closely about the front and sides of a window frame member, the inner side plate having an angularly projecting flange adapted to extend between a part of the window frame and the masonry of the building, a head projecting from the front of the plate member, and a fastening member passing through the window frame member and through both side plates of the anchor.

In testimony whereof, I have signed my name to this specification.

AINSWORTH BUCK.
